LOADING DEVICE

Albert R. Henry, Salina, Kans.

Application June 21, 1943, Serial No. 491,717

12 Claims.

(Cl. 214—139)

This invention relates to improvements in a loading device and has particular reference to a loading device mounted on and operable by a standard tractor.

The principal object of the present invention is the provision of a loading device including a standard tractor, the power unit of which operates the loader, and the frame of the loader attachment being of closed rectangular form to horizontally encompass the tractor.

Another object of the invention is the provision of a loader frame having vertical guide bars with forwardly projecting upper portions for guiding a boom carrying a bucket whereby the bucket is moved upwardly then upwardly and forwardly to the dumping position.

A further object of the invention is the provision of a loading attachment mounted on and operable by a tractor having a normally flexible frame, said attachment including a rectangular frame adapted to horizontally encompass said tractor, and having a fabricated cross member engaging said flexible tractor frame whereby the tractor frame is made rigid and also having a removable end section whereby the tractor may be horizontally moved from said attachment.

Another object of this invention is the provision of means interconnected with the tractor power unit whereby the operator may manipulate the attachment to perform various operations such as bulldozing, backfilling, loading, carrying, digging, etc.

Other objects are simplicity, economy and sturdiness of construction, ease and efficiency of operation and adaptability of use in performing many of the operations necessary for construction work.

With these as well as other objects, which will appear during the course of the specification, in view, reference will now be had to the drawings, wherein:

Fig. 1 is a side elevational view of a loading device embodying this invention, shown with the bucket in the lowered position and in the raised position in dotted lines.

Fig. 2 is a side elevational view of the reverse side of the loader with the bucket shown in the raised position, and dotted in the tripped position.

Fig. 3 is an enlarged fragmentary sectional view taken on line III—III of Fig. 4.

Fig. 4 is a plan view partly broken away to the connections of the loader attachment frame with the tractor frame.

Fig. 5 is a vertical section taken on line V—V

of Fig. 4 with the tracks outlined in dotted lines.

Fig. 6 is an enlarged sectional view taken on line VI—VI of Fig. 4.

Fig. 7 is a front elevational view of the loading device with the boom in the lowered position.

Fig. 8 is a fragmentary rear elevation of the loading device.

Fig. 9 is an enlarged front elevation view of the bucket trip lever mechanism.

10 Fig. 10 is a side elevation of the parts shown in Fig. 9.

Fig. 11 is an enlarged sectional view taken on line XI—XI of Fig. 4.

Fig. 12 is an enlarged central sectional view of 15 the cable driving mechanism taken on line XII—XII of Fig. 8.

Fig. 13 is a vertical sectional view taken on line XIII—XIII of Fig. 12.

Fig. 14 is a sectional view taken on line 20 XIV—XIV of Fig. 12.

Fig. 15 is a sectional view taken on line XV—XV of Fig. 12 with some parts left in elevation.

Fig. 16 is an enlarged sectional view taken on line XVI—XVI of Fig. 14.

25 Fig. 17 is an enlarged sectional view taken on line XVII—XVII of Fig. 7, showing the bucket operating lever about to enter the pull-rod loop.

Throughout the various views like reference characters refer to similar parts and the numeral 30 20 designates a tractor of the caterpillar or crawler type having tracks 22 supporting flexible frame members 24 which in turn carry the engine and associated parts. The supporting means connecting the engine and associated parts with 35 the frame member 24 includes driving axle 26 adjacent the rear of the tractor and the leaf spring member 28 positioned adjacent the front end of the tractor.

In normal use this flexible frame construction 40 permits independent raising and lowering of the front end of the frame member 24 for travel over irregular surfaces. A power unit such as an internal combustion engine 30 having a drive shaft 32 is provided to propel the tractor in the usual manner. The tractor also has the usual control means whereby the tractor with the attached loader can be maneuvered to properly operate the loading attachment.

Referring now to the loading device attachment which is adapted to be operated by the tractor and having connecting means whereby it is removably attached thereto, it will be noted that it comprises a rectangular frame 34 having parallel side rails 36, a fixed cross member 38, 45 and a removable rear section member 40 which

is adapted to be removed by removing bolts 42 and 44 at each side of the frame. When so removed, and with the frame supported in a horizontal position, it is quite apparent that the tractor may be moved into position between the rails 36 and the rear section member again positioned and bolted so that the frame will completely surround the tractor. The loader frame is supported on the tractor frame 24 by means of a fabricated cross member 46 and bearing plates 48 and 50 which are respectively in front of and at the rear of said fabricated cross member.

Referring to Figs. 4 and 5, it will be noted that the fabricated cross member 46 comprises two similar brackets 52 which are anchored to plates 54 integral with said rails 36 by means of bolts 56. These brackets are also secured to the top face of frame member 24 by bolts 58. These brackets are so constructed and positioned on the tractor that they may be left in position on the tractor frame when the loading attachment is removed without interfering with the normal operation of the tractor. The cross member 46 is provided with a central section 60 which is securely bolted to the inner ends of bracket 52 by bolts 62. When so positioned, the tractor frames 24 are secured against relative movement and the tractor frame becomes rigid. This feature is very important for the purpose of maintaining the loading attachment and its movable parts in proper alignment during the various operations necessary for loading, bulldozing, carrying, etc. Bearing plates 48 are carried by the forwardly extending extension 64 of the brackets 52 and simply rest on top of the tractor frames 24. The bearing plates 42 are removably secured to the side rails 36 by means of bolts 66.

Extending upwardly from the front end of each of the rails 36 is a vertically disposed guide bar 68 which is anchored to the side rails 36 by means of the diagonally disposed brace members 69. This guide bar is preferably made of cross sectional channel shape with the channels 70 opening outwardly as clearly shown in Fig. 4. The lower portion of guide bars 68 are disposed at substantially right angles to side rails 36 while the upper end portions thereof are angled forwardly and upwardly in like manner so as to present two like guide channels. The upper ends of guide bars 68 are joined together by cross member 72 and the cross bar 74 is disposed horizontally between the guide bars 68 intermediate the top and bottom of the guide bars. Vertical standards 76 are positioned between cross member 38 and cross bar 74 and are so constructed as to receive and protect the forward end of the tractor. Diagonal cross braces 78 serve to stabilize the lower portion of the guide bar structure.

Extending between cross bar 74 and cross member 72 are spaced apart vertically disposed angled bars 80, 81 and 83. All the frame parts except the rear section 40 are preferably welded together or may be riveted, bolted, or otherwise securely attached. A boom 82 is of substantially U-shape having side arms 84 and a cross header 86. Adjacent and to the rear of header 86 at each side of the boom is a bracket 88 carrying roller 90 which is adapted to travel in the adjacent channels 70 to guide the front end of the boom during the hoisting operation. It will be noted that the lower end of the channels 70 are closed by flange 92 to prevent the loader from dropping out of the guide channel 70.

5 Pins 94, best shown in Figs. 4 and 6 are removably secured to rails 36 by means of bolts 96, and extend outwardly from the rails to pass through slots 98 formed in the rear end portion of side arms 84. These pins being stationary on the frame, it is necessary that the slots 98 be sufficiently long to permit the upward movement of the boom without striking the outer end of the side arm. These pins 94 are very rigid in 10 construction and serve as abutments for the side arms when the attachment is operated as a bulldozer or when the bucket carried thereby is being loaded.

15 Referring to Fig. 1, it will be noted that the roller 90 is out of contact with the walls of the channel 70 when the pin 94 is contacting the inner end of the slot 98, thus preventing excessive loads on the roller construction. Extending forwardly of the boom 82 at each side thereof are arms 100 between which is mounted a bucket 102. This bucket is pivoted to arms 100 at 104 in such a manner that the bucket when loaded and in the raised position tends to tilt forward to release the load.

20 25 Latch means for securing the bucket against tilting is best shown in Fig. 3 and comprises a detent 106 welded to the lower rear portion of the bucket and reinforced by means of an angled bar 108 which is secured lengthwise of the bucket. 30 A bracket 110 secured on the forward face of the cross member 86 serves as one bearing for a rigidly disposed shaft 112, while the other end portion of the shaft is mounted in a bracket 114 which is also secured to cross member 38. The 35 upper portion of bracket 110 is bifurcated to receive latch 116 which is urged forwardly to engage detent 106 by a spring 118 disposed under compression between latch 116 and the bracket 110. The lower end of the bracket 110 is offset 40 at 120 to receive the lower projecting end 122 of the detent 106. This offset serves as a stop to operate in conjunction with latch 116 to maintain the bucket against lost motion.

45 Referring now to Figs. 9 and 10, the shaft 112 is provided with an operating device comprising a Y-shaped lever 124 pivotally mounted on said shaft and secured against forward movement by stop bar 126 carried by bracket 128 which is securely mounted on cross member 38. A lever member 130 securely welded to shaft 112 and having a cross bar 132 which normally rests against the rear side of lever 124 serves to cause shaft 112 to oscillate when lever 124 is operated rearwardly by means of the pull rod 134. Since 50 the latch 116 is welded to shaft 112 and the spring 118 urges the latch forward it is quite apparent that the lever 124 will also be urged to the forward position against stop bar 126. The principal function of lever 124 is to permit the engaging of the detent 106 by latch 116 when the bucket is returned to its normal position without moving lever 124.

55 The pull rod 134 is attached to a slide block 136 mounted on a bar 138 carried by brackets 140 and 142 which in turn are mounted on tubing 144 hereinafter described. Block 136 is also provided with an operating handle 146 by means of which the operator may release the latch 116 and permit the bucket to dump. A cushioning spring 148 mounted on bar 138 in the path of slide block 136 serves to cushion the pull of the operator. It will be noted that the upper end 150 of lever 124 is curved forwardly and has a forwardly projecting finger 152 for properly 70 75 positioning the pull rod 134 on the lever. The

pull rod 134 has an elongated open loop 154 which is normally positioned as shown in Fig. 1 to rest on cross bar 14, and projecting outwardly beyond the guide bar 68. Beveled centering lugs 156 serve to maintain the loop 154 in alignment with the upper end of lever 124.

As the boom is raised from its lowered position shown in Fig. 1 the upper end portion 158 of the lever will be threaded into loop 154 and the guide rod will be moved upwardly therewith to take the position shown in dotted lines in Fig. 1. This movement is accomplished without releasing latch 116 so that the operator may release the bucket at his convenience.

The means for resiliently limiting the dropping of the bucket during the dumping operation, shown in Fig. 11, comprises a tubing 158 secured to the back side of the bucket and having a spring 160 mounted therein to rest on a bottom ledge 162 with a chain 164 extending therethrough to engage a follow up block 166. The chain is secured at its outer end to a pin 168 secured to the header 86 so that when the bucket is dropped, chain 164 will be extended and spring 160 compressed thus absorbing the impact of the load. Chains 164 may be shortened or lengthened to vary the discharge angle of the bucket.

Reference will now be had to Figs. 12, 13, 14, 15 and 16.

The drive shaft 32 of the tractor motor is controlled by the operator to rotate in either direction and is interconnected with shaft 158 by coupling 160. Housing 162 is rigidly secured to engine housing 164 by means of brackets 166. This housing 162 is vertically partitioned at 168 to form chambers 170 and 172 and has a removable top plate 174 for convenience of installing and adjusting the parts contained therein. Shaft 158 is mounted in bearing 174 and extends into chamber 170 to receive brake drum 176 rotatably mounted thereon. Brake drum 176 also is provided with internal spur gear teeth 178 which mesh with pinions 180 rotatably mounted on studs 193 carried by spider 182, which in turn is rigidly mounted on shaft 158 by means of pilot 186 extending into a recess formed in shaft 158 and bearings 188, 190 formed in partition 168 and the outer wall of housing 162 respectively. Securely mounted on the inner extremity of shaft 158 is a gear 192 which meshes with the planetary pinions 180 carried by spider 182.

Mounted rigidly on shaft 158 in compartment 172 is a dry brake drum 196 and a cable reel 198. A brake band 200, see Fig. 14, is associated with brake drum 176 and is normally loose thereon and may be set by oscillating shaft 202 to move head 204 against the T-head 194 formed on brake band control rod 206. The shaft 202 is rotatably mounted in a bearing 208 carried by housing 162 and is provided at its upper end with an operating lever 210 which is interconnected by link 212 to a hand operated lever 214 pivoted intermediate its ends at 216 to a bracket 218. A slide rod 220 with adjusting screw 222 and spring 223 is provided to resiliently and adjustably position one end of the brake band which is slidably mounted on rod 208.

The brake drum 196 best shown in Fig. 15 is provided with a brake band 224 which is shown in the released position. One end of the brake band is provided with a cam-faced lug 226 which co-acts with cam 228 secured against rotation

for longitudinal movement on shaft 230 which extends outwardly from housing 162 to receive a lever 232. Interposed between cam 228 and the bearing boss 234 on housing 162 is a compression spring 236. This spring is so wound that when the cams are in the position shown, the spring will be released so that the brake band will not clampingly engage the drum 196. However, when the reel operating means is inactive and the cams are rotated to cause them to separate, then the spring 236 will be under compression to urge the brake band 224 against drum 196 with sufficient force to secure shaft 158 against rotation. The other end of brake band 224 is adjustably secured by means of slide rod 238 and adjusting screw 240. Lever 232 is connected by means of bar 242 to the lower extremity of the hand operated lever 214.

It will be noted that the brake band operating mechanisms are so constructed and operated that when brake band 200 is set, brake band 224 will be released and when band 224 is set, band 200 will be released.

This structure allows for proper operation of reel 198 while shaft 158 is being driven by engine shaft 32. Reel 198 is provided with a roll of cable 244 which extends through an opening 246 formed in the wall of housing 172, then upwardly through a tubing 248 which is removably pivoted to ears 250 carried by housing 172 by means of trunnions 252. Tube 248 is pivotally mounted by shaft 254 with horizontally disposed tube 144 through a short tubing 258 which normally contacts a fixed collar 260 secured to the tube 144. The forward end of tube 144 is pivotally mounted at 262 to arms 264 carried by cross bar 14. Rotatably mounted in bearings 266 carried by bars 81 and 82 is a shaft 268 carrying a drum 270 for rotation therewith. The lower edge of this drum is in tangential alignment with the center of tubing 256 so that the cable 244 extending over a pulley 272 mounted on shaft 254 will extend longitudinally through tubing 144 to wind on drum 270 as clearly shown in Figs. 1, 2, 12 and 13. Helically fluted drums 274 are also rigidly mounted on shaft 268 to receive the elevating cables 276. Each of these cables is attached at its one end by means of clamp 278 to cross bar 86, then extends over a pulley 280 which is mounted on the overhead shaft 282 carried in brackets 284 which in turn are secured to vertical members 80, 81, 82 and guide standard 78.

The cables 281 are spaced apart so as to engage the load adjacent each of its outer ends to stabilize and prevent side tilting thereof. It is quite apparent that when engine shaft 32 is being rotated that the operator through the use of hand lever 214 may easily raise or lower the boom to any desired position intermediate its top and bottom limits. The bucket when raised from the ground may be dumped regardless of its height by simply operating lever 124. If the load has been lifted sufficiently so that lever 124 engages pull rod 134, then the operator may easily operate the bucket trip by grasping and pulling handle 146.

The following means is provided to limit the upward travel of the boom. This means comprises a lever 286 pivoted at 288 to a standard 70 290 carried by guide bar 68. The free end of lever 286 is connected by rod 292 to hand operated lever 214. A vertically disposed rod 294 is connected at its one end to the free end of lever 286 and extends through a guide bearing 296 carried adjacent the top of guide bar 68. Ad-

Justably mounted on rod 194 is a transversely disposed pin 298 which is adapted to be contacted by means of a spring member 300 carried by bracket 88. When the parts just described are in the position shown in Fig. 2, the shaft 184 will be secured against rotation so that the boom will be secured in its limited upward position and cannot be caused to travel any further upwardly. The operator may now move lever 214 further forward to operate brake bands 200 and 224 to 10 lower the boom. The tubes 248 and 144 with their hinged connections to the stationary parts not only function to compensate for the spring movement of the forward end of the tractor but also serve as a housing for the moving parts and 15 to brace the cable carrying parts.

It is to be understood that the engine control means of the tractor remains in constant operable position and that the only extra lever required to operate the loading attachment is the hand operated lever 214 so that when the loading attachment is removed as previously described, the tractor is in condition for immediate general use.

The raising, dumping and lowering of the bucket 102 has been described and it is quite apparent that after the bucket is dumped it may be lowered to contact the ground then the tractor is manipulated to return the bucket to the latched position as shown in Fig. 1. When so positioned the bucket may be filled by simply driving the tractor forward.

While the device has been shown with a bucket, it is the intention of the applicant to utilize this same attachment for bulldozing, backfilling, etc. by installing a blade in the place of the bucket. When so altered it will be noted that the principal load will be transmitted through arms 84 to pins 94 and since these pins are located adjacent the rearward end of the tractor, a very effective hitch is obtained, since the forward end of the tractor will not have a tendency to be raised upwardly.

From the above detailed description of the invention, it is believed that the construction and operation thereof will at once be apparent and while there is herein shown and described the preferred embodiment of the invention, it is nevertheless to be understood that minor changes may be made therein without departing from the 50 spirit and scope of the invention as claimed.

What I claim is:

1. A loading attachment adapted to be mounted on and operated by a tractor, comprising a closed frame adapted to encompass a power tractor and to be removably attached thereto, vertically disposed guides fixedly secured to said frame, a boom shiftably mounted adjacent its forward end in said guides and slidably mounted at its rear end on pins carried by said frame, means for elevating said boom along said guides as it slides along said pins.

2. A loading attachment adapted to be mounted on and operated by a tractor, comprising a closed, horizontally disposed frame adapted to encompass the tractor and to be removably attached thereto, vertically disposed guides fixedly secured to said frame and having their upper end portions formed to extend outwardly from said frame, a boom shiftably mounted at its forward end in said guides and slidably mounted at its rear end on pins carried by said frame, and means operable by the power unit of said tractor to elevate said boom along said guides as it slides along said pins, and means to secure said 75

boom at any predetermined point of its vertical travel.

3. A loading attachment adapted to be mounted on and operated by a tractor, comprising a horizontally disposed closed loading attachment frame adapted to horizontally encompass said entire tractor and to be removably attached intermediate its ends thereto, guide bars having their lower end portions secured in right angled relation to said frame and their upper portions inclined upwardly and outwardly therefrom, a boom shiftably mounted at its forward end on said guides and slidably mounted at its rear end on pins carried by said frame, and means operable by said tractor to elevate and move forwardly said boom along said guide bars as the rear end thereof slides along said pins.

4. A loading attachment adapted to be mounted on and operated by a tractor, comprising a horizontally disposed frame removably attached to said tractor, guide bars having their lower end portions secured in substantially right angled relation to said frame and their upper portions inclined upwardly and outwardly therefrom, a boom shiftably mounted at its forward end on said guides and slidably mounted at its rear end on pins carried by said frame, means operable by said tractor to elevate and move forwardly said boom along said guide bars as the rear end thereof slides along said pins, means to automatically limit the height of elevation of said boom a bucket carried at the outer end of said boom, latching means to normally secure said bucket in the upright position, and means adjacent the rear end of said boom operable to release said latching means to permit the dumping of said bucket.

5. A loading attachment adapted to be mounted on and operated by a tractor, comprising a horizontally disposed closed frame adapted to horizontally encompass said tractor and to be removably attached thereto, guide bars having their lower end portions secured in right angled relation to said frame and their upper portions inclined upwardly and outwardly therefrom, a boom shiftably mounted at its forward end on said guides and slidably mounted at its rear end on pins carried by said frame, means operable by said tractor to elevate and move forwardly said boom along said guide bars as the rear end thereof slides along said pins, and means to automatically limit the height of elevation of said boom, a bucket carried at the outer end of said boom, latching means to normally secure said bucket in the upright position, and means adjacent the rear end of said boom, operable to release said latching means to permit the dumping of said bucket.

6. A loading attachment adapted to be mounted on and operated by a tractor, comprising a closed frame adapted to horizontally encompass said tractor and having a removable end portion whereby the tractor may be moved bodily and horizontally from said frame, vertically disposed guides secured to the forward end of said frame, and having their upper end portions curved forwardly and upwardly, a boom shiftably mounted at its forward end in said guides, and mounted at its rear ends on pins anchored to said frame, a bucket tiltably mounted on the outer end of said boom, latch means adapted to normally secure the bucket in the loading position, means for elevating said boom along said guides, and manually operable means to release said bucket

latch when the bucket is in the raised position whereby the load is dumped.

7. The combination with a tractor having a normally flexible frame and a power unit, of a loading attachment including a frame adapted to horizontally encompass the tractor and having a cross member secured to the flexible tractor frame whereby the tractor frame is made non-flexible, a boom adjustably carried by said loading attachment frame, and means driven by said tractor power unit whereby said boom is adjusted.

8. The combination with a tractor of the caterpillar type having a normally flexible frame, of a loading attachment including a frame adapted to horizontally encompass the tractor and having a cross member intermediate its end portions secured to the flexible tractor frame whereby the tractor frame is made rigid, a removable end section at one end of said frame whereby the loading attachment may be horizontally removed from said tractor.

9. The combination with a tractor having normally flexible frame and a power unit, of a loading attachment including a frame adapted to horizontally encompass the tractor and having a cross member secured to the flexible tractor frame intermediate its end portions whereby the tractor frame is made rigid, a boom adjustably carried by said loading attachment frame, means driven by said tractor power unit whereby said boom is adjusted, and a removable section at one end of the loading attachment frame, whereby the end of said frame may be opened to permit relative horizontal movement of the tractor and loading attachment for complete separation thereof.

10. The combination with a tractor having a frame and a power unit, of a loading attachment including a rectangular frame adapted to horizontally encompass said tractor frame, vertically disposed grooved guide bars having forwardly and upwardly extending upper portions and being secured at their lower ends to the forward end of said rectangular frame, a boom slidably mounted at its rear portion on said rectangular frame and provided at its front portion with rollers

adapted to move in the grooves of said guide bars, and means operable by said tractor power unit to raise the front end of said boom whereby it is caused to raise vertically, then forwardly and vertically as the boom rollers travel in said guide bars.

11. A loading attachment adapted to be mounted on and operated by a tractor, comprising a closed frame adapted to horizontally encompass said tractor and having a removable end portion whereby the tractor may be moved horizontally from said frame, vertically disposed guides secured to the forward end of said frame, and having their upper end portions curved forwardly and upwardly, a boom shiftably mounted at its forward end in said guides, and mounted at its rear ends on pins anchored to said frame, a bucket tiltably mounted on the outer end of said boom, latch means adapted to normally secure the bucket in the loading position, means operated by said tractor, including hingedly mounted tubings for supporting and housing an operating cable extending from the rear to the front of the tractor, for elevating said boom, and manually operable means to release said bucket latch when the bucket is in the raised position.

12. A loading attachment adapted to be mounted on and operated by a tractor, comprising a closed frame adapted to horizontally encompass said tractor and having a removable end portion whereby the tractor may be moved horizontally from said frame, vertically disposed guides secured to the forward end of said frame, and having their upper end portions inclined forwardly and upwardly, a boom shiftably mounted at its forward end in said guides, and mounted at its rear ends on pins anchored to said frame, a bucket tiltably mounted on the outer end of said boom, latch means adapted to normally secure the bucket in the loading position, means operated by said tractor, including hingedly mounted tubings for supporting and housing an operating cable extending from the rear to the front of the tractor, for elevating said boom, and manually operable means to release said bucket latch when the bucket is in the raised position.

ALBERT R. HENRY.
